United States Patent Office

Des. 217,714
Patented June 2, 1970

217,714

CART FOR GAS TANKS

John P. Salsgiver, West Acton, Mass., assignor to United Technical Corporation, West Concord, Mass., a corporation of Massachusetts

Filed Mar. 21, 1969, Ser. No. 16,372

Term of patent 14 years

Int. Cl. D12—02

U.S. Cl. D14—3

Fig. 1.

*Fig. 2.Fig. 3.Fig. 4.*FIG. 1 is a perspective view of the cart for gas tanks showing my new design;

FIG. 2 is a plan view;

FIG. 3 is a view in front elevation; and

FIG. 4 is a view in side elevation.

The tank shown in broken lines in FIG. 1 is included for illustrative purposes only.

I claim:

The ornamental design for a cart for gas tanks, as shown and described.
